UNITED STATES PATENT OFFICE.

GEORGE L. PIERCE AND KNUT DJERF, OF BROOKLYN, NEW YORK, ASSIGNEES TO A. G. SPALDING & BROS., OF JERSEY CITY, NEW JERSEY, A CORPORATION OF NEW JERSEY.

LAST FOR FORMING LEGGINGS.

1,275,086.

Specification of Letters Patent.

Patented Aug. 6, 1918.

Application filed November 2, 1917. Serial No. 199,909.

To all whom it may concern:

Be it known that we, GEORGE L. PIERCE and KNUT DJERF, a citizen of the United States and subject of the King of Sweden, respectively, and residents of Brooklyn, New York, have invented certain new and useful Improvements in Lasts for Forming Leggings, of which the following is a specification.

10 Our invention relates to a last for forming articles, such as leather leggings and it consists in the features and combination and arrangement of parts hereinafter described, and particularly pointed out in the claims.

15 In the accompanying drawings;

Figure 1 is a perspective view of the last embodying our invention collapsed.

Fig. 2 is a transverse sectional view taken near the top of the last with the last in closed or collapsed position.

Fig. 3 is a transverse sectional view with the last in extended position, and with the leather being molded in place thereon.

25 Fig. 4 is a front view of the last and wedge member.

Fig. 5 is a view of the main face of one of the members with the wedge in position to hold the sections expanded.

The last is made up in sections 1 and 2, each of these sections having a contour to provide the desired shape to the part of the legging with which it comes in contact, the two sections or halves of the last being divided from each other along a plane extending

30 from front to rear of the legging and they are connected or joined together at their rear edges, so as to allow the sections to have a hinge-like separating or closing movement in relation to each other, and while

40 this connection may assume different forms we illustrate as an advantageous form a pair of pins 3 extending from one section into

45 sockets in the other section, the pins fitting loosely in these sockets 4, so as to provide for the necessary amount of movement. Each

section is provided on its inner face and near its front edge with a channel or way 5 extending longitudinally of the section and at a slight distance from its front edge, leaving

50 a rib portion 6 between said groove or way and the front of the section. These grooves or ways are so disposed in relation to each other that they register and are adapted to receive a wedge member, which

55 is of such cross sectional form that it pro-

vides side ribs 7 and a main or central face portion 8, the said side ribs being adapted to fit in the channels or ways in the inner faces of the sections and the main or face portion of the wedge being adapted to come substantially flush with the front edges of the sections, between which edges the said face portion is adapted to move. This face portion is curved at 9 to conform to the curve of the ankle portion of the last, so that when the wedge is driven fully to its proper position the face of the wedge will form practically a continuation of the surface of the sections because of the curve at 9 conforming to the curve of the ankle portion of the sections.

The front edges of the sections are slightly more widely separated at the upper portion or calf portion of the last than at the ankle portion, these edges converging downwardly from the upper to the lower ends of the last. The lower end of the wedge is of a width less than the normal size of the channel left between the two sections when the said sections are closed, so that the wedge may be readily introduced into this channel, and force the sections apart at their front edges, while the rear edges of the sections remain in contact with each other and have a hinge-like action. The dowel pins prevent any longitudinal displacement of one section in relation to the other.

The wedge is formed in one piece, it having a portion at 10 extending beyond the curved or forming portion which latter reaches to the point 11 from the upper end of the wedge, and including the curved portion at 9, this extension 10 being the first part of the wedge in action when it is thrust into place to separate the sections of the last.

In the use of the appliance the leather from which the legging is to be made is cut to a pattern. The edges are brought together and stitched and the leather is then soaked in water, and drawn over the last or form while it is in collapsed or closed condition. The wedge is now driven into place, whereby the sections of the last are gradually separated with a pivotal action in respect to each other, and this separation continues until the point 11 of the wedge reaches the lower edge of the last when it will be seen that the curved portion 9 of the wedge will be conforming to and providing a continua-

tion of the reduced rounded surface at the ankle.

This will spread the leather to the proper form and thereafter the leather is tacked to the upper part of the form and is permitted to dry. That part of the legging which has been stitched up is then cut away, the knife being drawn along each side of the stitching and the stitched seam being thrown 10 away. The leather blank thus provided is ready for receiving the straps and for finishing.

It will be observed that the length of the wedge is such that in starting the operation of spreading the sections a long handle portion will be provided at the large end of the wedge making it convenient for the operator to thrust the wedge into place and when the wedge is properly seated the front 20 extension thereof will be projecting therefrom, so that by using this as a handle portion the wedge can be thrust backward and thus removed from between the sections and the surrounding legging.

25 What we claim is:

1. A last or form comprising sections separable from each other and a wedge member extending between said sections for separating them, the said wedge member having a portion with a face to conform to the face of the last throughout the extent of the latter and with a forward extension beyond the first mentioned portion forming a tapered continuation of the wedge, substantially as described.

2. A last comprising sections with a wedge inserted between the edges of said sections at one side and means for connecting the sections together at the other side, said connecting means permitting the sections to have a hinge-like action and serving to hold the sections together against longitudinal displacement, substantially as described.

45 3. A last comprising sections with a wedge inserted between the edges of said sections at one side and means for connecting the sections together at the other side, said connecting means permitting the sections to have a hinge-like action and serving to hold the sections together against longitudinal displacement, said connecting means being detachable by moving the sections a part, substantially as described.

55 4. A last comprising sections with a wedge inserted between the edges of said

sections at one side, said sections having sockets and dowel pins forming a connection between the sections at the other side thereof, said dowel pins fitting in said sockets and said sections when spread assuming an angular relation, substantially as described.

5. A last for shaping leggings comprising an elongated body formed in sections divided from each other in a plane extending from front to rear, the rear portion of the said body being curved to conform to the ankle and calf of the leg, and the front portion of said body being substantially 70 straight along a line of separation between the sections, the inner faces of the sections having each a channel near the front portion only of said body and a wedge member having side ribs or portions to fit the 75 channel and having a main body portion to fit the front edges of the sections and with a face to conform to the shape of the front of the last, substantially as described.

6. A last for shaping leggings comprising an elongated body composed of two sections divided from each other longitudinally of the body and in a plane extending from the center of the front to the center of the back and a wedge member with means 85 for guiding the same between the sections adjacent the front thereof, said sections when spread by the wedge member assuming an angular relation to each other, said wedge member being longer than the length 90 of the sections and tapered substantially uniformly from end to end, substantially as described.

7. A last composed of sections the opposing faces of which are in contact at one side of the last and adapted to fulcrum one on the other at their point of contact, said sections having at or near the opposite edge of said faces channels extending longitudinally and a wedge member inserted in said 100 channels and adapted to separate the sections at this point and position the sections at an angle to each other, substantially as described.

8. A last composed of sections and a 105 wedge inserted between them at one edge only thereof and separating the sections into angular relation, substantially as described.

In testimony whereof, we affix our signatures.

GEORGE L. PIERCE.
KNUT DJERF.
